UNITED STATES PATENT OFFICE

2,650,742

DISPENSER FOR GRANULAR MATERIALS

Charles B. Overbaugh, Denver, Colo.

Application May 22, 1950, Serial No. 163,514

6 Claims. (Cl. 222—190)

1

This invention relates to dispensers for granulated materials, and more particularly to dispensers commonly used to hold salt, sugar and other such condiments whose particles tend to deliquesce and cohere to form lumps or a solid mass in the presence of moisture, and has as an object to provide in such a dispenser a new and improved dryer element effective to provide a sufficient degree of dehydration of the air within the container to prevent lump formation of the granulated particles therein.

Another object of this invention is to provide, in a dispenser for granulated materials, a new and improved structure for holding a dryer element which permits the dryer element to be quickly and easily installed or removed.

Another object of this invention is to provide, in a dispenser of granulated materials, a new and improved form of dryer element which is adapted to be disposed throughout the length of the dispenser body to thereby effectively dehydrate the air within the dispenser throughout its length and so avoid lump formation or crusting of the granulated particles in particular regions.

Yet another object of this invention is to provide a new and improved dryer element for dispensers of granulated materials and a new and improved structure within the dispenser for holding the dryer element which, together, form an exceedingly simple and economical combination which is adaptable for use in a wide variety of types and constructions of dispensers.

With these and other objects in view, all of which more fully hereinafter appear, my invention comprises certain new and novel constructions, combinations and arrangements of elements as herein described and as defined in the appended claims, and illustrated, in preferred embodiment, in the accompanying drawing in which:

Figure 1 illustrates, in section, a conventional salt shaker having the present invention incorporated therein.

Figure 2 is a section as taken on the indicated line 2—2 at Fig. 1.

Figure 3 illustrates, in section, another type of salt shaker with the present invention incorporated therein.

Figure 4 illustrates, in section and on a reduced scale, a spout type dispenser, such as is commonly used to contain granulated sugar, having the present invention incorporated therein.

In regions where there is appreciable humidity there is ever present the problem of granulated substances, such as salt and sugar, becoming

2

caked or hardened or lumpy through a tendency of such particles to deliquesce to a slight extent and thereby cohere to each other. While such action does not impair the quality of the substance, it does render it difficult to use in an ordinary type of dispenser which is designed for free-flowing granulated materials. Such a dispenser is the conventional salt shaker illustrated at Figs. 1, 2 and 3. To remedy this undesirable condition of lumping or crusting of the material, there have heretofore been developed various substances which act as dryers or dehydrating agents, and various attempts have been made to incorporate such dryers in conventional dispensers such as salt shakers, the usual mode of application being to place the dryer in the bottom of the dispenser. This is not fully effective because the granulated material is dehydrated only in the lower region of dispenser adjacent the dryer. Still other arrangements have been devised which overcome this objection, but they are so bulky that the effective volume of the container is reduced to a large extent. The present invention comprises, in essence, a drying element formed as a cylindrical spire adapted to extend throughout the length of the dispenser at its center, being held in position by a stake upstanding the dispenser bottom.

In the embodiment of the invention illustrated at Figs. 1 and 2, the salt shaker 10 is formed as a cylindrical cupped body 11 having a threaded rim portion 12, and a perforated lid 13 suitably threaded to be turned onto the rim 12 to close the shaker except for the perforations in the lid. A cylindrical pointed stake 14 centrally upstands from the bottom 15 of the body 11, and this stake may be formed integral with the bottom 15, as illustrated, or it may be attached thereto in any other suitable manner not shown, such mode of attachment depending upon the nature of the material from which the body 11 and bottom 15 are made.

The drying element 16 may assume several forms, but is in essence a cylindrical spire having a diameter somewhat greater than the stake 14, and it may be formed of various absorbent substances such as cellulose, for example, which are known in the art, or it may be of porous structure and carry various absorbent substances, many of which are known to the art. The base 17 of this element is opened interiorly to form a tubular portion 18 whereby it may slidably encase, and thereby be seated upon, the stake 14. This drying element 16 is obviously a simple and easily packaged unit, simply and easily remov-

able from and replaceable in the salt shaker during, and in little more time than is required by, the refilling of the shaker. Moreover, the element is adapted to extend throughout the effective length of the shaker and, therefore, keeps the entire contents of the shaker sufficiently dehydrated to insure free movement of the granulated particles.

In alternate construction of a salt shaker, such as illustrated at Fig. 3, the shaker 10' is formed with its body 11' and lid 13' as an integral unit, and to provide access to the interior for purposes of charging with salt, there is provided a centrally disposed orifice 19 at the bottom 15'. This orifice is conveniently closed by a cork 20, and in the present invention the stake 14' is connected to the cork 20 to upstand the bottom 15' when the cork is positioned in the orifice 19.

It is seen that with this construction the drying element 16 must be proportioned to be inserted into the orifice 19, and that its application is extremely simple, it being necessary to merely place the drying element over the stake 14' on the cork 20 and the element will be properly positioned when the shaker is closed by the cork.

The dispenser illustrated at Fig. 4 is of a different type from the others illustrated, and comprises a body 11" having a threaded rim 12" similar to parts 11 and 12 of Fig. 1. However, the lid 13" is not perforated but is provided with a spout 21 through which granulated material may be poured. This spout is normally closed by a hinged lid 22 to prevent the ingress of moisture from the atmosphere. In this construction the stake 14 is similar to those in the other figures and upstands the bottom 15 to carry a drying element 16 as hereinbefore described. However, where all of the granulated material is to be poured from the spout, the drying element may be suitably formed with a curved end 16 so that said end may be directed and held toward the spout to accelerate the flow of granulated materials thereto.

While I have herein described and illustrated many details of construction of my invention, alternatives and equivalent constructions, within the scope and spirit of my invention, will occur to those skilled in the art, and therefore it is my desire that I be limited in my protection only by the spirit and proper scope of the appended claims.

I claim:

1. A dispenser for hygroscopic granular material having a container with a dispensing top thereon, comprising, in combination, a generally cylindrical pin upstanding from the bottom and centrally of the container and having a pointed top, and a generally cylindrical member composed of absorbent material and having a central, cylindrical cavity whereby the member is adapted to selectively slidably encase and be uprightly supported by, and slidably removed from said pin, said member being substantially the length of said container.

2. A dispenser as defined in claim 1, wherein said container has an orifice centrally through its bottom and a plug normally closing said orifice and forming a part of the bottom but being removable from said orifice, said pin being carried by and centrally of said plug.

20 3. The dispenser defined in claim 1 wherein said dispensing top is a perforated lid.

4. The dispenser defined in claim 6 wherein said dispensing top is a lid containing a spout.

25 5. The dispenser defined in claim 6 wherein the top has an off-center opening and the top portion of the absorbent member is deflected toward said opening.

6. A dispenser for hygroscopic granular material having a container with a dispensing top thereon including, in combination, a generally cylindrical pin upstanding from the bottom and centrally of the container and a member composed of absorbent material having a central cylindrical cavity whereby the member is adapted to selectively slidably encase and be uprightly supported by and slidably removed from said pin, said member being substantially the length of said container and having its body portion, at least to the extent of the reach encasing the 40 pin, substantially cylindrical.

CHARLES B. OVERBAUGH.
